BERNARD A. ENGHOLM, OF LAKEWOOD, OHIO, ASSIGNOR TO THE ROLA COMPANY, OF CLEVELAND, OHIO, A CORPORATION OF OHIO

LOUD SPEAKER

Original application filed May 30, 1930, Serial No. 457,552. Divided and this application filed August 12, 1932. Serial No. 628,579.

This invention relates to electrodynamic loud speakers, and particularly to the voice coil form, which embodies part of the structure thereof. The present application is a 5 division of my prior application, Serial No. 457,552, filed May 30th, 1930.

One form of loud speaker which is in general use utilizes a tympanum in the form of a cone with a moving coil mounted adjacent the apex end thereof. Considerable difficulty has been experienced in making a 10 coil form, which would have sufficient strength to withstand the necessary handling, incident to the assembling operations, 15 and which at the same time would be sufficiently light in weight to keep the mass and moment of inertia at a minimum.

One coil form heretofore used has embodied a heavy paper cylinder on which the coil 20 has been wound. To provide sufficient strength to permit attachment of the form to the cone and supporting spider, however, it has been necessary to reinforce the form with an additional layer or collar of paper. The 25 form projected beyond the end of the collar and had to be glued onto the inner face of the cone. This form of construction is objectionable, for it has been difficult to prevent the end turns of the coil from slipping off the 30 form during the winding and subsequent handling operations. Furthermore, the use of an additional supporting collar increases the number of manufacturing operations while the connection between the form and 35 cone has necessitated a delay in the assembling operation, until an adequate period of time has elapsed for the glue to dry.

Another form, which has been used, comprises a cylindrical member of rigid material, which is nearly equal in thickness to the 40 depth of the winding. The member is then turned down on a lathe to form a peripheral groove in which the coil may be wound. This obviously is an expensive procedure and 45 is objectionable, as it does not overcome the difficulty of providing satisfactory means for connecting the form to the cone.

An object of the present invention, therefore, is to make a voice coil form that will be 50 extremely light in weight and yet have the

desired rigidity to hold the coil in proper position.

A further object is to provide a form which can readily be made to assume the desired cylindrical form with a high degree of accuracy, and which will maintain such shape for an indefinite period during operation.

Referring now to the drawing, Fig. 1 is a vertical section taken through a loud speaker assembly, embodying my invention; Fig. 2 is 60 a plan view of a blank from which a voice coil form may be made; Fig. 3 is a section through a forming mold with the blank positioned therein; Fig. 4 is a perspective view showing the shape of the form at the completion of the forming operation; Fig. 5 is a perspective view showing the voice coil assembly on the form; Fig. 6 is an end view of the coil form attached to the supporting spider, and Fig. 7 is a perspective view of one of 70 the collars, which may be used for connecting the coil form to the spider.

The invention is shown in connection with a loud speaker of the cone type, having a diaphragm or tympanum 10, which is preferably frustro-conical in shape, and which may be fastened at the base thereof to a collar 11, which in turn is flanged at 12, and is adapted to be fastened between the flange of a housing 13 and a clamping ring 14. The housing 80 may carry a spider 15, which supports the diaphragm adjacent the apex end thereof. To this end, the diaphragm is shown as being fitted between a collar 16 and a voice coil form, as indicated in general at 17. The housing 13 in turn may be mounted on a field coil structure, which comprises a shell 20 that has a central core 21, carried thereby, and a face plate 22, which is positioned between the shell and the housing and which coacts with 90 the core to provide an air gap within which the voice coil 23 is positioned. The field coil 24 surrounds the core and is disposed within the shell.

The present invention relates more particularly to the structure of the voice coil form and contemplates the provision of a form which is extremely light in weight and yet which has sufficient rigidity to obtain the desired cylindrical form and to hold the voice 100

coil thereon. The form may be made in various ways, but the preferred arrangement includes the steps of cutting a strip of material 19, such as paper, having a thickness of from 5 four to eight thousandths of an inch and having a length equal to the circumference of the form. The strip is then bent into the shape of a cylinder with the ends in abutting engagement, and is placed in a cylindrical mold 10 25. To facilitate accurate alignment of the ends of the strip when bent to cylindrical form, I provide a small tab 26 on one end and a corresponding notch 27 on the other end. Thus, when the strip is bent into cylindrical 15 shape, the tab fits into or meshes with the notch. Furthermore, when the blank 19 is initially made, I provide pairs of openings 28 and 29, as is shown in Fig. 2. The openings 28 are in one longitudinally extending row 20 and those indicated at 29 are in a parallel row. These openings are utilizable for holding the ends of the wire in position during and after the winding operation.

It is desirable that the coil 23 be disposed 25 between the shoulders on the form. To this end, the form may be bent to provide the desired shoulders by pressing it outwardly against the walls of the die. Accordingly, the mold 25 is shown as having an annular 30 groove 30, formed on the inner surface and spaced above the bottom thereof. A second groove 31 may then be disposed below the groove 30 and adjacent the region occupied by the lower edge of the blank. The blank 35 is then forced outwardly into the grooves by means of a plunger 32, which has a head 33 of soft rubber and which operates when forced into the mold through the form to stretch the paper and cause it to assume the contour of 40 the mold. This, therefore, provides one shoulder in the form of a bead 35 at one end of the form, and a rib 36 between the ends of the form. The space between the rib and bead then constitutes a groove 37, into which 45 the coil 23 may be wound. The bead and adjacent end of the rib, therefore, act as limiting shoulders to assist in keeping the coil in place on the form. Furthermore, the position of the rib forming groove 30 in the mold 50 is such that the openings 28 are disposed at one end of the rib, while the openings 30 are disposed at the other end of the rib. Thus, when the ends of the coil are passed through an opening 29 and then through an opening 55 28, the wire lies within the hollow of the rib and is thus in alignment with the inner surface of the coil form.

The openings through which the wires extend has thus important manufacturing advantages. For example, one end of the wire 60 may be quickly threaded through one pair of openings and then bent backwardly upon itself. It can thus be satisfactorily held against movement during the winding operation without requiring it to be looped or

twisted around any member. When the winding operation is completed, the opposite end may be threaded through the remaining pair of openings. During the winding operation cement is used for securing the coil 70 turns in place. The openings, therefore, serve as a means of bringing out the leads and at the same time holding the coil in proper position until the cement is dry.

To provide an expeditious manner of connecting the coil form to the cone, I fasten a light metallic ring 40 onto the spider, adjacent the inner wall 41 thereof, and I cover the end portion 42 of the form with cement or glue, and insert it into the ring 40. The apex end of the cone 10 is split for a distance about one-eighth of an inch to form segments or tabs, and these are then bent until they extend parallel to the axis of the cone. They are then inserted into the end 80 of the form and are glued or cemented thereto. To hold the tabs firmly against the form, I may use the metallic ring 16, which is slightly in excess of the inside diameter of the cone tabs. The ring has a conical extension 45, which is tapered in conformity with the cone. After the surface of the ring is glued or cemented, it is then pressed against the tabs, thus forcing them outwardly against the voice coil form, and in 85 turn forcing the form against the ring 40. Thus, the entire assembly is securely locked together.

While I have illustrated and described one method of making the coil form, it is to be 90 understood that other methods are within the scope of my invention. For instance, the form may be cut initially from a paper cylinder, the cylinder dropped into the mold, and then pressed outwardly and stretched 95 until it conforms to the desired shape.

An important advantage of a voice coil 100 form which is made in accordance with my invention is the fact that the material is stretchable and that it has a uniform thickness throughout. Thus, I obtain a strong 110 yet light form, which makes the voice coil more sensitive to current fluctuations and therefore more efficient in sound reproduction than any of the heavier coil forms heretofore known. Furthermore, by following the preferred method of making the article, I obtain a die-formed structure, which can be accurately made, and which will maintain 115 its shape for a long period of time.

I claim:

1. A voice coil form, having spaced openings arranged in pairs, each pair cooperating to provide a passageway on the inner side of the form for carrying the leads of a voice 12. coil into and out of the form.

2. A cylindrical voice coil form of substantially uniform thickness throughout, said form having a coil receiving portion at one end thereof and having a diaphragm engag- 13

ing portion adjacent the other end thereof, and a raised portion therebetween, the raised portion providing passageways through which the leads of a coil on the form may be passed.

3. A voice coil form comprising a substantially tubular member, having a coil positioning abutment thereon, said form being provided with a wire receiving perforation adjacent the abutment, and having substantially uniform thickness throughout.

4. A voice coil form comprising a single strip of material having spaced shoulders defining a coil receiving groove, and having wire receiving perforations therein adjacent one end of the groove, the material of the form being of substantially uniform thickness throughout.

5. A form comprising a single strip of material having a bead formed therein adjacent one end thereof, and having a shoulder formed therein intermediate the ends thereof, the shoulder and bead having the same thickness, as the remaining part of the form and cooperating to provide a coil receiving groove.

6. A coil comprising a substantially cylindrical member of uniform thickness throughout and having spaced shoulders to provide a coil receiving groove, and also having a wire receiving perforation therethrough adjacent one end of the groove.

7. A voice coil form comprising a single strip of material of cylindrical form, of uniform thickness, and having spaced shoulders therein, there being pairs of spaced openings extending through the form, the openings cooperating with the shoulders to provide passage through which the leads of the coil may be passed into the form and then out of it, and bent back upon themselves to lock the coil against movement with relation to the form.

8. A form comprising a substantially cylindrical member, having means defining a coil positioning abutment including a shoulder upset from the material of the form, and having a perforation adjacent the shoulder extending from the outer to the inner face of the form, the shoulder providing a cavity on the face of the form to receive said terminal lead.

9. A form comprising a substantially cylindrical tubular member having a recess on the inner face thereof, and having an aperture adjacent the recess for providing a passageway through the form for the lead of a coil positioned on the form.

In testimony whereof, I hereunto affix my signature.
